COMBINATION KITCHEN AND SEWING MACHINE CABINET

Carl J. Lerch, Cleveland, Ohio, assignor to White Sewing Machine Corporation, Lakewood, Ohio, a corporation of Delaware

Application August 6, 1952, Serial No. 20,922

Term of patent 14 years

(Cl. D33—12)

FIG. 1.

Des. 175,515

FIG. 2.

FIG. 3.

Fig. 1 is a perspective view taken from one front corner of a combination kitchen and sewing machine cabinet showing my new design with the sewing machine head illustrated in dotted lines,

Fig. 2 is a perspective view taken from the other front corner than that from which Fig. 1 is taken, and

Fig. 3 is a front elevational view of the combination kitchen and sewing machine cabinet in closed position.

The back side of the combination kitchen and sewing machine cabinet is plain.

I claim:

The ornamental design for a combination kitchen and sewing machine cabinet, as shown and described.
